FIG. 3

FIG. 4

UNITED STATES PATENT AND TRADEMARK OFFICE
CERTIFICATE OF CORRECTION

PATENT NO. : Des. 326,255

DATED : May 19, 1992

INVENTOR(S) : Arthur D.B. Graham, John G. Roncz,
Graham Swannell

It is certified that error appears in the above-identified patent and that said Letters Patent is hereby corrected as shown below:

On the title page, item (75):

A co-inventor's name is misspelled. The name "Graham Swanell" should read --Graham Swannell--.

Signed and Sealed this
Sixth Day of July, 1993
